UNITED STATES PATENT OFFICE.

WILLIAM C. HEDGCOCK, OF CHICAGO, ILLINOIS, ASSIGNOR TO AMERICAN STEEL
FOUNDRIES, OF NEW YORK, N. Y., A CORPORATION OF NEW JERSEY.

BRAKE.

1,165,669.

Specification of Letters Patent. Patented Dec. 28, 1915.

Application filed September 23, 1915. Serial No. 52,170.

To all whom it may concern:

Be it known that I, WILLIAM C. HEDGCOCK, a citizen of the United States, and resident of Chicago, in the county of Cook and State of Illinois, have invented certain new and useful Improvements in Brakes, of which the following is a specification.

My invention relates to car brakes, and has particular reference to an improvement 10 on the construction shown in the patent to Posson, No. 789,879, May 16, 1905. In the construction of the patent referred to, means are provided for maintaining a pair of 15 brake beams in parallelism by the use of parallel motion means comprising a bar extending from one beam to the other and connected to each beam by means of two links or levers. The present invention relates to means for applying such improvements to 20 beams already in use.

The invention will be more readily understood by reference to the accompanying drawings, wherein—

Figure 1 is a side elevation of my improved means, the parts being shown as applied to a brake beam, the compression and tension members of which are shown in section, and Fig. 2 is an end view of the construction shown in Fig. 1.

In the drawings, it will be seen that a 30 brake beam to which the improvement is applied may comprise a compression member 10, tension member 11 and strut 12. A brake lever 13 is pivoted in the strut at 14, and at its lower end is pivoted to a pair of 35 long links 15, which extend and are attached to a beam in exactly the manner shown herein. To the outer end of the bars 15 is pivoted a link 16, the upper end of which is 40 pivoted to a casting 17. This casting is provided with an apertured ear 18, which lies between two similar apertured ears 19 integral with the strut 12. A foot, or projection, 20 extends beyond the lug 18 and 45 lies against the strut 12. The lower portion of the casting is provided with an arcuate recess 21, which fits the tension rod 11. A

pin or rivet 22 extends through the apertured lugs 18, 19, and serves to securely hold the extension or casting in place and provides a simple means for the connection of the parallel motion means to a brake beam of the common construction. 50

Obviously the construction is capable of considerable modification, and such modifications as are within the scope of my claims I consider within the spirit of my invention. 55

I claim:

1. In brake construction, the combination of a brake beam having a strut and provided 60 with an apertured lug, parallel motion means extending between adjacent beams, and an extension secured to the apertured lug on said strut and providing means for the attachment of said parallel motion 65 means, substantially as described.

2. In a brake, the combination of a beam having a strut and provided with an apertured lug in substantially the plane of the tension member of said beam, parallel motion means extending between adjacent beams, and a casting secured to the apertured lug on said strut, and adapted to provide 70 means for the fastening of said parallel motion means, substantially as described. 75

3. In brake construction, the combination of a beam having a strut, a brake lever pivoted to said strut and having a portion extending on each side thereof, an apertured 80 lug on said strut, a casting having a pair of ears and adapted to be secured to said apertured lug, a bar secured to one end of said brake lever and adapted to extend to an adjacent beam, and a link connecting the end 85 of said bar to the apertured ears on said casting and adapted to provide a parallel motion means, substantially as described.

Signed at Chicago, Illinois, this 20th day of September, A. D. 1915.

WILLIAM C. HEDGCOCK.
